UNITED STATES PATENT OFFICE

RUDOLPH FRANK STEHLIK, OF CHICAGO, ILLINOIS, ASSIGNOR TO RESERVE HOLDING COMPANY, OF KANSAS CITY, MISSOURI, A CORPORATION OF DELAWARE

TELEPHONE HAND SET

Application filed March 30, 1928, Serial No. 265,989, and in Belgium December 20, 1927.

The present invention relates to improvements in or relating to handset combinations as used in telephone instruments. Such handsets comprise, as is well known, a handle having a receiver at one end and a transmitter supported at the other end, so arranged that when the receiver is brought to the ear the transmitter comes in front of the mouth.

The object of the present invention is a handset construction in which simplicity and cheapness of manufacture are combined with great durability, and the principal feature of the invention is that both the ear cap and the transmitter cap are screwed directly on to the receiver and transmitter casings respectively, which casings are moulded in a single moulding including the handle between the casings.

In one form of handset it has been usual to provide a separate horn or mouthpiece secured to or by the transmitter cap having an opening which must be arranged specially to come opposite the mouth of the user.

Further features of the invention concern the particular shape of the receiver handle, and a novel mouthpiece, which is capable of receiving sound in a lateral direction irrespective of the direction in which the sound may come. This latter feature is particularly important, as it is by this means a mouthpiece separate from the cap may be avoided, so that the two components can be made in a single piece, thereby considerably economizing in the cost of manufacture.

These and other features of the invention will be better understood by referring to the accompanying drawings, in which Fig. 1 shows a section through a handset with receiver and transmitter casings. The receiver and transmitter, which are constructed in the form of capsules, are omitted for the sake of clearness. Fig. 2 shows a front view of the novel handset, while Fig. 3 shows a side view with the ear cap and mouthpiece cap omitted. Fig. 4 shows an enlarged section on the line A—B of Fig. 1, while Fig. 5 shows a similar enlarged section on the line C—D of Fig. 1.

Referring to Fig. 1, it will be noted that the handset comprises a single moulding, includ-

ing a handle portion 10, a receiver casing 11 and a transmitter casing 12. The moulding incorporates a brass or other metallic tube 13 extending from the receiver casing 11 to the transmitter casing 12 and serving to reinforce the handle, at the same time providing an opening through which conductors from the receiver may extend to the transmitter casing 12, and so through the opening 14^a therein to the bell-box, together with the 55 cords from the transmitter. The shape of this handset is novel, in that both the receiver casing 11 and the transmitter casing 12 have their axes somewhat out of the normal with respect to the straight portion 14 of the handle portion 10. This arrangement, together with the curved shape of the portion of the handle opposite to the straight portion 14, produces a rather novel shape, which is pleasing to the eye, and at the same time is particularly convenient for use. A further advantage is that the eccentric position of the brass tube in the centre of the handle increases the strength of the handle to a greater degree than if it was central. As regards 70 manufacture it is advantageous, in that it enables the receiver cap 15 and the transmitter cap 16 to be screwed directly on to the casings 11 and 12 respectively. In certain constructions it has been necessary to design the receiver cap so as to have a raised portion at the end furthest from the transmitter so as to give an appropriate angle to the handle. This is necessary where the receiver casing 75 is normal or substantially normal to the straight side 14 of the transmitter handle. With the present inclination, however, the receiver cap can be uniform all around, and consequently no special means have to be provided to insure that it comes to rest with a 80 particular part of the cap in a particular position, such as is necessary in the cases above referred to where an auxiliary screwed fitting is provided to insure the proper alignment of the cap.

While the above remarks apply to the receiver casing and cap, they are more particularly applicable to the transmitter casing and cap. As the mouth of the user is usually between the transmitter casing and 100

the receiver cap, the sound waves from the user pass in a lateral direction across the transmitter, and for this reason the caps have hitherto been provided with a mouthpiece having an opening solely in the direction of the mouth, thus necessitating that the mouthpiece must be definitely aligned with respect to the handset, and consequently an expensive adjusting means had to be provided to insure this result. An important feature of the present invention in this connection, therefore, is the construction of a transmitter cap, which, while having openings admitting sounds from all lateral directions, is yet efficient in directing the sound waves generated by the user on to the diaphragm of the microphone. One form of carrying this into effect is shown in the accompanying drawings, the transmitter cap 16 being formed of a single stamping having a shape which may be said to resemble a hemisphere or spherical segment with the upper portion dented inwards so as to be substantially conical. This shape will be recognized in the section in Fig. 1 where the hemispherical portion is indicated by the reference 17, while the conical portion is indicated by the reference 18. In the hemispherical portion 17 is a series of holes 19 (which are better seen in Fig. 2) which extend all round the hemispherical portion of the cap at equal distances apart. Of course, when the cap is screwed into position it is impossible to determine in advance exactly where the cap will rest, but it will be appreciated that with a cap as constructed according to the present invention, in whatever position it comes to rest there will be openings 19 facing the mouth of the user. Furthermore, the conical member 18 will serve to deflect the sounds coming from the user towards the diaphragm, and thus insure that the microphone is actuated by a sufficient volume of sound waves as to ensure efficient and satisfactory transmission.

It should be noted that the exact shape described is not the only shape possible. An alternative construction, for instance, could comprise a series of quarter-spheres, which were hollow, had their flat sides projecting towards the outer ring of the cap and were pressed out from a flat metal blank. This would serve a similar purpose of offering a means of collecting sound from the mouth of the user and directing it on to the transmitter cap. The exact shape of the handset, which is preferred to other shapes, will be better understood by referring to Fig. 3 and Figs. 4 and 5, from which it will be noted that the section of the handle is circular throughout its length and tapers gradually from the centre to the ends, where the receiver and transmitter casings are joined to it. The tube, it will be noted from Fig. 1, is parallel to the straight side, and the curvature of the outer side of the handle conforms

very appropriately with the inclinations of the transmitter and receiver casings to the straight side of the handle. It is believed it is the first time a handle with such a neat appearance has been evolved, combining with its neat appearance cheapness of manufacture and efficiency.

What is claimed is:

1. In a transmitter mouthpiece or cap, openings facing in a lateral direction uniformly on all sides and a reflecting surface for directing sound waves received in a lateral direction on to the transmitter.

2. In a transmitter mouthpiece or cap, a single stamping having a convex surface at its outer edge with openings therein spaced regularly all around the circumferences and a convex central surface serving to reflect sound waves received through said openings inwards to the transmitter.

3. A transmitter mouthpiece comprising a circular outer convex portion, a plurality of openings arranged around the circumference of said portion, and another convex portion formed inside said first convex portion for receiving sound waves impinged thereon from said openings and for directing them at an angle onto the transmitter.

4. A transmitter mouthpiece comprising a single circular convex shaped unit with a plurality of openings spaced regularly around the circumference thereof, and a conical convex portion formed in the center of said unit and projecting opposite said openings so as to direct sound waves received through said openings directly onto the transmitter.

5. A transmitter mouthpiece comprising a circular convex shaped unit with a plurality of openings spaced around the circumference thereof, a conical convex portion formed in the center of said unit and projecting opposite said openings so that sound waves are received through said openings and diverted by said conical portion to the transmitter unit, and means for supporting said mouthpiece unit on said transmitter unit in such a manner that irrespective of the position to which said mouthpiece is rotated said openings and conical portion are always in the same operative relation with respect to the sound waves and transmitter.

In witness whereof, I hereunto subscribe my name this sixth day of March, A. D. 1928.

RUDOLPH FRANK STEHLIK.
